UNITED STATES PATENT OFFICE.

JOHN H. O'ROURKE, OF WATERBURY, CONNECTICUT.

TUBE-DRAWING PLUG.

Application filed March 26, 1923. Serial No. 627,897.

To all whom it may concern:

Be it known that I, JOHN H. O'ROURKE, a citizen of the United States, residing at Waterbury, in the county of New Haven 5 and State of Connecticut, have invented certain new and useful Improvements in Tube-Drawing Plugs, of which the following is a specification.

My said invention relates to a plug for 10 tube drawing machines, and it is an object thereof to provide a plug which shall have all the desirable characteristics of those now in use while at the same time it will provide for greater economy in time, labor and ma- 15 terial.

Referring to the accompanying drawings, 20 which are made a part hereof and on which similar reference characters indicate similar parts,

Figure 1 is a side elevation of the device in use, the die and tube being shown in section,

Figure 2 an elevation of the plug on an enlarged scale, and

Figure 3 an elevation of a plug of the type hitherto employed for this purpose.

In the drawings reference character 10 indicates a die which contacts with the exterior surface of a tube which is to be reduced in diameter and extended in length in the well-known operation of tube drawing. A plug 11 is adapted to be positioned on a rod 12, the latter being so mounted as to be capable of retraction from the die.

Usually the rod is pivoted at its rear end so that it can be swung upward from the die for removal or replacement of the plug. At the end of the rod is a nut 13 here shown as separated from the plug by a washer 14 and serving to hold the plug in place against a shoulder on the rod formed by reducing the outer end of the same, as indicated in dotted lines in Figure 2.

The plug 11 tapers regularly from the 45 middle toward each end as shown with a taper of about sixteen thousandths to the inch. It is adapted to be inserted within the die, the precise position being determined by an adjustment at the rear end of the draw-bench extension (not shown). In the use of the device the tube 15 is drawn between the die and the plug, the latter being set so as to determine the inner diameter of the tube and the thickness of its wall. Tubes 50 such as 15 are successively placed over the plug and drawn by the usual means until

the surface of the plug at the point of contact becomes worn sufficiently to interfere with proper operation of the device when the plug, if of the old type shown in Figure 60 3, must be discarded so far as drawing tubes of the specified size is concerned though it can still be utilized for drawing larger or smaller tubes according to the distance be- 65 tween the worn part and the respective ends of the plug. It may still be ground down to a smaller size. My improved plug can be re-ground on the same principles as illustrated in Figures 1 and 2, so that it still has two wearing surfaces instead of one as on a 70 plug of the former type. A new plug is then placed on the rod and the parts are re-set to bring the same to the correct position relative to the die.

With my device all that is necessary is to 75 reverse the plug on the rod and bring the parts to the same position as before, the two tapering ends being exact duplicates of each other thus doing away with any need of re-setting. The rod is secured at its pivoted 80 end (not shown) in such a manner that it can be moved bodily with the plug to adjust the same relative to the opening in the die, this being to compensate for wear on the inner surface of the die in addition to the advantage of being able to reverse the plug 85 without re-setting of parts.

In the use of the plug tubes will be drawn on it until an annular depression is formed 90 in the plug, when a plug of the old type must be replaced with another while mine is merely reversed, and used until a similar groove is worn at the other end. The old plug may be set to draw tubes of different sizes, say at five different points of the part 16 up to about the dotted line located 95 midway of the length of the plug. It is never set so as to use the surface on the part 16', as the plug loses its balance and chatters in a manner to interfere with the work. By making the plug slightly longer, with 100 about the proportions shown in the drawings I am able to set it to draw at from four to five points at each end of the plug, which is in balance regardless of which end 105 is forward. Furthermore said positions for the two ends are duplicates of each other, so that a plug can be used twice as long on tubes of the same size, thus saving time 110 on the job, and cutting down the number of plugs needed in the mill.

It is to be noted not only that the same

plug may be used twice as long as a plug of the old type, but that twice as many tubes may be drawn with it as with the plugs now used, these conditions resulting in saving of time and labor both in making plugs, in handling and transporting them and in drawing tubes. In addition to this the saving of material is an important advantage, the material from which they are made being high priced tool steel and each double plug requiring very little more steel than the old single plugs, the new plugs being a little longer and being thicker at the middle.

15 Having thus fully described my said invention, what I claim as new and desire to secure by Letters Patent, is:

1. In a tube drawing machine, a die, a rod arranged to be positioned co-axially with the die or to be retracted therefrom and a reversible plug removably mounted

on the rod said plug having oppositely directed frusto-conical surfaces adapted to be selectively positioned concentrically with the die, substantially as set forth.

2. In a tube-drawing machine having a longitudinally adjustable rod arranged to hold a plug in fixed position relative to a die during the drawing operation, the combination of a reversible plug tapering from the middle toward each end, and means to secure the same removably on the rod, substantially as set forth.

25 In witness whereof, I have hereunto set my hand and seal at Waterbury, Connecticut, this sixteenth day of March, A. D. nineteen hundred and twenty-three.

JOHN H. O'ROURKE. [L. s.]
